(57) **CLAIM**

The ornamental design for a coffee additive dispenser, as shown and described.

DESCRIPTION

FIG. 1 is a top left perspective view of coffee additive dispenser showing our new design;

FIG. 2 is a front view thereof;

FIG. 3 is a left side view thereof; the right side view being a mirror image thereof;

FIG. 4 is a rear view thereof;

FIG. 5 is a top view thereof; and,

FIG. 6 is a bottom view thereof.

The right side of the new design (not shown) is a mirror image of FIG. 3.

1 Claim, 3 Drawing Sheets
